UNITED STATES PATENT OFFICE.

DIEDRICH WILLIAM KRELLWITZ, OF ST. CATHARINES, ONTARIO, CANADA.

POLE.

No. 884,171.

Specification of Letters Patent. Patented April 7, 1908.

Application filed November 19, 1906. Serial No. 343,985.

To all whom it may concern:

Be it known that I, DIEDRICH WILLIAM KRELLWITZ, of the city of St. Catharines, in the county of Lincoln, in the Province of Ontario, Canada, civil engineer, have invented certain new and useful Improvements in Poles, of which the following is a specification.

My invention relates to improvements in poles and the object of my invention is to construct a pole of steel concrete, of such a cross section at every point in its length that the steel concrete will be strong enough to take up the stresses caused by erecting, without injury to the pole and provide means for ascending the pole with the greatest degree of safety.

The pole consists essentially of a steel skeleton pole frame united with concrete forming a steel concrete pole. The said steel skeleton pole frame consists of steel uprights and steel horizontals. The uprights being arranged and constructed in detail as hereinafter more particularly explained.

Figure 1. is a side view of a pole constructed in accordance with my invention. Fig. 2. is a view showing the steel skeleton frame of the pole. Fig. 3. is a longitudinal section of the pole at right angles to Fig. 1. Fig. 4. is a cross sectional plan through the top of the pole. Fig. 5. is a cross sectional plan through the middle of the pole. Fig. 6. is a cross sectional plan through the bottom of the pole.

Any pole which is subject to horizontal pulls and great pulls due to erecting said pole has considerable transverse stress which tends to bend and break the pole by rupturing the side of the pole which is in compression and by pulling apart the opposite side which is in tension.

My invention is designed to withstand the compressive and tensile stresses and avoid the breaking of the pole during erection.

In a suitable mold the concrete body marked "B" is cast with the steel skeleton frame embedded therein.

The uprights used for the entire length are of a uniform cross sectional area.

The lowest portion "P" being made of a high carbon steel and the portion "P¹" above said lower portion to be of a less carbon steel and the next portion "P²" above the latter of a still lower carbon steel and so on continuing to the top of the pole so that the pole will be strongest at the bottom where the greatest stresses are brought to

bear on the pole and gradually diminish in strength from the bottom upwardly. In other words, the steel rods or sections of the uprights are of greater strength at the bottom of the pole than at the top. The horizontal pieces A for holding the steel rods in spaced relation are wires coiled around the rods as at a, only a few of such rods being shown in full view for clearness of illustration, the remaining rods being shown diagrammatically.

In order to designate the different carbons steel and that they may not be put in their wrong positions they are made of different shapes having the same cross sectional area.

I am aware of different patented shaped bars but it is not the object of my invention to patent a particular shaped bar.

The horizontal pieces marked "A" of the said steel skeleton frame are acting as ties so as to avoid the vertical members from bulging out sidewise, and also to strengthen the concrete from cracking caused by the erection of the pole and the expansion and contraction of a large variation in the temperature or in other words to resist thermal stresses.

In molding I provide ladder rungs which are set in the soft concrete when the pole is being molded which gives a greater degree of safety to a man climbing the pole.

I am aware that the Canadian patent number ninety-two thousand six hundred and eighty-eight was granted on April 18th, 1905, for a pole having longitudinal reinforcing rods of varying cross sectional area but the object of my invention is to have a uniform cross sectional area as specified.

I am also aware of poles built before invention No. 92688, in France and Italy, having the combination of steel with the main body of concrete. And I therefore know that the combination of steel located in proximity of exterior of the pole with the main body of concrete is not new. But I am not aware of poles having the combination with the main body of concrete, of re-inforcing uprights, each of a uniform cross sectional area; said uprights being made of different carbon steel decreasing from bottom portion to the top portion.

What I claim as my invention is

1. In poles the combination with the main body of concrete, of re-inforcing uprights of the same cross sectional area throughout the

entire length of pole, each upright being made in portions of different grades of carbon steel and each successive portion from the bottom of the pole decreasing from a high carbon steel to the top of the pole as specified.

2. In a pole, the combination of a steel structure composed of sections arranged end to end and extending longitudinally of the 10 pole, each section including longitudinal members of carbon steel of a different grade from those of an adjacent section, with a body of concrete in which the structure is embedded.

15 3. In a pole, the combination of a metal structure composed of spaced uprights of uniform cross section at all points and having portions of greater strength at the bottom and decreasing in strength upwardly, hori-

zontal members extending around the spaced 20 uprights engaging therewith, with a body of concrete in which the structure is embedded.

4. As an article of manufacture, a steel structure for a pole, said structure comprising a number of sections each consisting 25 of a plurality of steel rods, and means for connecting the rods together in fixed relation, the rods of adjacent sections being of different grades of steel and having their ends rigidly secured to form continuous members 30 extending longitudinally of the pole.

In testimony whereof I have hereunto set my hand and seal, this twenty-seventh of October A. D. 1906.
